UNITED STATES PATENT OFFICE.

SIMEON S. JACKSON, OF BOSTON, MASSACHUSETTS, ASSIGNOR TO THE STAFFORD COMPANY, OF BOSTON, MASSACHUSETTS, A CORPORATION OF NEW JERSEY.

WARP STOP-MOTION FOR LOOMS.

1,239,792.

Specification of Letters Patent. Patented Sept. 11, 1917.

Application filed March 13, 1915. Serial No. 14,246.

To all whom it may concern:

Be it known that I, SIMEON S. JACKSON, a subject of Great Britain, residing at Readville, Boston, in the county of Suffolk, State of Massachusetts, have invented a certain new and useful Improvement in Warp Stop-Motions for Looms, of which the following is a specification, reference being had therein to the accompanying drawings.

10 My invention is designed more particularly for employment in connection with fine warps having a considerable number of ends to the inch. One general object of the invention is to provide for splitting the 15 warp-threads, *i. e.*, separating them from union with one another, and to prevent them from either remaining united to one another or becoming joined or knit together in their progress through the loom. By accomplishing this object I eliminate chafing and wear 20 of the warp-threads, and greatly reduce the number of breakages thereof. Another object is to render the individual warp-threads readily traceable back to the drop- 25 wires, so as to enable repairs to the warp-threads to be effected easily. Other objects are to reduce crowding at the drop-wires and thereby reduce chafing, and to facilitate access to the drop-wires and warp- 30 threads.

An embodiment of the invention is illustrated in the drawings, in which latter,—

Figure 1 is a view showing certain portions of a loom in section in a vertical plane 35 extending from front to rear in the loom, with the said embodiment applied thereto. Fig. 2 is a plan view of the parts that are shown in Fig. 1.

Having reference to the drawings,—

40 A portion of the breast-beam of a loom is shown at 1, and a portion of the lay-beam at 2. A portion of one lay-sword is shown at 3, Fig. 1. The reed carried by the lay rail being marked 4^a, and Fig. 1 shows a shuttle 5 upon the lay-beam. Harness-frames are shown at 6, 6^a, 6^b, 6^c. Warp-threads *a*, *a*¹, *a*², *a*³, are shown extending from the rear of the loom through the eyes 45 of the heddles mounted in said harness-frames, and through the dents of the reed 4, to the fell, where they are united in the web 7 produced by the combination of the

warp-threads with the weft-thread which is interwoven therewith by means of the shuttle 5.

The drop-wires 8, 8^a, of the warp-stop-motion are hung upon the warp-threads between two transversely-extending rods 9, 9^a, and in this instance the said drop-wires are disposed in two banks which are guided by their guide-bars 10, 10. The rear drop-wires, 8, are hung upon warp-threads extending over both of the said rods. The front drop-wires, 8^a, are hung upon warp-threads which pass over the rear rod, 9, and under the front rod, 9^a. At 11 is a warp-rest located between the two banks of drop-wires and below the warps. Those portions of the warp-stop-motion which coöperate with the drop-wires in indicating the breaking or excessive slackness of the individual warp-threads, and in bringing about the arrest of the working of the loom, are not shown. They may be of any approved character.

In carrying my invention into effect the entire series of warp-threads is arranged to pass over the rear (right-hand) rod 9, and to rest thereon. One half of the warp-threads of the said series pass over the front (left-hand) rod, 9^a, and the other half below the same. In arranging the threads over and under the front rod 9^a they are disposed two by two. That is to say, two threads are disposed above the said rod 9^a the next two below the same, the next two above the same, the next two below, and so on alternately. The warp-threads also are drawn two by two through the drop-wires of the two banks. That is to say, two threads which lie side by side at the same side of the front rod 9^a respectively are drawn through two drop-wires located side by side in one bank.

The warp-threads which are drawn two by two through adjoining pairs of the drop-wires as just explained, and are disposed in alternating pairs located above and below the left-hand rod 9^a, are drawn through the heddle-eyes of the harness-frames in an order which splits and separates from each other the individual threads composing every pair of warp-threads. Thus, one thread of each pair is drawn through a heddle-eye of a harness-frame pertaining

to one of the planes of the shed that is formed for the reception of the weft-threads, while the other warp-thread of such pair is drawn through a heddle-eye of a harness-frame pertaining to the opposing plane of the shed. The results of this are that the respective pairs of warp-threads are split or divided in front of the left-hand rod 9^a, and that during the weaving operations the two threads constituting a pair at front rod 9^a extend forward to the harness-frames along different lines, at all times except when the harness-frames are exactly even. In addition, the individual warp-threads are readily traceable back to the drop-wires, so that repairs to the threads are easily effected, and the grouping of the drop-wires reduces crowding and chafing, and facilitates access to the drop-wires and warp-threads. These are the particular objects of the invention. In the drawings four harness-frames are shown. It is to be understood that in practice they are coupled or connected together to work in pairs for plain weaving. The warp-threads are drawn in 1, 3, 2, 4; 1, 3, 2, 4 order through the heddle-eyes of the said harness-frames. It will be observed that one warp-thread, *a*, of a given pair of warp threads, passes from the bottom of the left-hand rod 9^a, to a heddle-eye of the first harness-frame, 6, counting from the rear of the loom, while the adjoining thread, *a*¹, of the same pair passes from the bottom of the said rod through a heddle-eye of the third harness-frame, 6^b, also counting from the rear. These two threads, therefore, are caused to form parts of the opposite planes of the shed represented in Fig. 1, and when the shed is open they diverge from each other from the rod 9^a forward. It will also be observed that one thread, *a*², from the top of the left-hand rod 9^a passes through a heddle-eye of the second harness-frame, 6^a, counting from the rear, while the adjacent thread, *a*³, of the same pair passes from the top of the said rod 9^a through a heddle-eye of the fourth or front harness-frame, 6^c, so that the two threads of this pair form parts of the opposite planes of the open shed. Thus, between the left-hand rod 9^a and the harness-frames the warp-threads are divided into four planes instead of remaining either in a single plane or in two planes as heretofore usual. In the case of the shed-formation that is represented in Fig. 1, the threads *a*¹ which pass from the under side of the left-hand rod 9^a to the third harness-frame, 6^b, counting from the rear, and the threads *a*² that pass from the top side of the said rod to the second harness-frame, 6^a, also counting from the rear, cross one another in front of the said rod, and between the latter and the harness-frames. When the shed-formation is re-

versed, the threads *a*¹, *a*², become uncrossed and the threads *a*, *a*³, become crossed.

The illustrated arrangement has the advantage, further, that in applying the warps, harnesses, etc., to the loom the division of the threads to separate them for the application of the left-hand rod 9^a in the relations shown in Figs. 1 and 2 is readily effected, simply by depressing the first and third harness-frames and raising the second and fourth. This separates the threads in pairs, as required in accordance with the invention. In case only two harness-frames, working oppositely, should be employed, with the threads *a*, *a*², passing through the eyes of the heddles of one of the said frames, and the threads *a*¹, *a*³, passing through the eyes of the heddles of the other frame, the division of the warp-threads into pairs for the insertion of the rod 9^a may be effected by other methods known to weavers. More than two harness-frames may be grouped together to move in unison, in which case the warp-threads will be divided into more than four sets or series and the order of drawing-in through the eyes of the heddles of the different harness-frames will be correspondingly modified, but the general arrangement of the warp-threads in front of rod 9^a will approximate that represented in the present drawings.

I claim as my invention:

1. In combination, a transverse warp-support for the warp-threads in a loom, a lease-rod in advance of said warp-support by which the warp-threads passing over said warp-support in a single plane are divided by alternating groups into two planes, one whereof passes over the said lease-rod and the other below the same, a bank of drop-wires hung upon alternating warp-threads adjacent the warp-support, a second bank of drop-wires hung upon the remaining warp-threads in the lower plane of warp-threads adjacent the said lease-rod, and oppositely-working harness-frames pertaining to opposite planes of a shed, said harness-frames having the threads composing each of the said groups drawn in alternating order through the heddle-eyes of the respective harness-frames so as to be divided between the said opposite shed-planes.

2. In combination, a transverse warp-support for the warp-threads in a loom, a lease-rod in advance of said warp-support by which the warp-threads passing over said warp-support in a single plane are divided by pairs into two planes, one whereof passes over the said lease-rod and the other below the same, a bank of drop-wires hung upon alternating pairs of the warp-threads adjacent the warp-support, a second bank of drop-wires hung upon the warp-threads of the remaining pairs in the lower plane of warp-threads adjacent the said lease-rod,

and oppositely-working harness-frames pertaining to opposite planes of a shed, said harness-frames having the threads composing each of the said pairs drawn in alternating order through the heddle-eyes of the respective harness-frames so as to be divided between the said opposite shed-planes.

In testimony whereof I affix my signature in presence of two witnesses.

SIMEON S. JACKSON.
